HEINRICH MELTZER, OF RATIBOR, GERMANY.

APPARATUS FOR EXAMINING THE EXACT SPHERICAL FORM OF BALLS.

SPECIFICATION forming part of Letters Patent No. 610,071, dated August 30, 1898.

Application filed December 16, 1896. Serial No. 615,920. (No model.)

To all whom it may concern:

Be it known that I, HEINRICH MELTZER, a subject of the King of Prussia, residing at Ratibor, in the Kingdom of Prussia, Germany, have invented new and useful Improvements 5 in Apparatus for Examining the Exact Spherical Form of Balls, of which the following is a specification.

In the manufacture of steel balls a considerable number of balls are found to be not of perfectly spherical or round shape. It is usual to neglect small inaccuracies in this respect, and for many purposes small inaccuracies up to 0.01 millimeter are not harmful; 10 but a greater inaccuracy of diameter of a ball must certainly be noted, although it is very difficult to separate with certainty balls that are faulty in this respect. The cause of this is that a ball that is not perfectly round has a 15 very large number of equal diameters and that repeated measurements must be made in order to discover the fault. Heretofore the examination of balls for these faults was effected in a very tedious and difficult manner— 20 namely, the balls were placed on a board and held against a strong light and then carefully examined along their surfaces upon which the light fell, with the object of ascertaining whether they were perfectly round. The 25 board would then be repeatedly shaken, with the object of causing the balls to assume different positions, so as to bring fresh surfaces of the balls into the light. It is obvious that for such examination an excellent eyesight is 30 required in order to note even comparatively considerable differences and that the results of examinations of large quantities by different persons have varied very widely. These 35 difficulties and inaccuracies are completely 40 obviated by the employment for the purpose of examining balls with respect to their perfect roundness of the method which forms the subject of the present invention and which constitutes the principle of construction of the 45 machine hereinafter described. This method is based on the principle that a perfectly round ball when placed on a perfectly smooth inclined surface will, under similar circumstances, always roll down the same path. 50 Consequently the balls are led onto smooth inclined surfaces permitting free escape of diverted bodies over the side edges and are

allowed to roll down repeatedly over the same. Every perfectly round ball always maintains the direction imparted to it by a feeding device and will pass into the collecting-box provided at the lower end of the rolling-surface, whereas an imperfectly round ball in its first, second, &c., passage along the rolling-surface will diverge from its direction and fall down 55 on one side over the rather narrow rolling-bars. By allowing the balls to roll down repeatedly over the inclined rolling-surfaces the result will be that it is insured with a considerable degree of certainty that each time 60 a different periphery of the ball will run along the rolling-surface, whereby a result is obtained that is sufficiently accurate for practical purposes.

The accompanying drawings illustrate a 70 machine which may be employed for carrying out the method herein described.

Figure 1 is a side elevation of the machine. Fig. 2 is a front end elevation of the machine. Fig. 3 is a plan of the machine. Fig. 4 illustrates a detail of the machine, and Fig. 5 is a detail sectional view of the guide at the head of the incline on the line 5 5 of Fig. 4.

Upon the standard A is arranged the ball-receptacle B, in the slotted bottom of which 80 there is mounted a feed-wheel C, that is provided with holes c corresponding to the size of the balls, said wheel C being revolved by means of the wheels X Y Z. Under the feed-wheel C there is arranged a guide-channel D, 85 with which connects the first rolling-bar E', having a perfectly smooth surface. This surface is connected by means of a semicircular arc-shaped part F', which is also formed with a guide-groove f, with the next bar E'. 90 The bar E' is further connected to F², F² to E³, E³ to F³, F³ to E⁴, and E⁴ to F⁴. These bars terminate in a box G, which is divided by a partition g into two compartments G' and G².

The mode of operation of the machine is as 95 follows: The balls fall first into the holes c of the feed-wheel C and are then brought by the latter onto the guide-channel D. From there the balls roll over the bar E', arc-shaped piece F', &c., into the compartment G' of the 100 box G. This will, however, be the case only when the balls are perfectly round, because then they do not diverge from their straight path, and they always run along the center of

the rolling-bars. Now an imperfectly round ball, on the contrary, is deflected from its path, and since the bars E are but slightly wider than the diameter of the ball the ball will fall 5 over the bars E down into the box G². This operation may be repeated several times.

The machine is further provided with an apparatus which serves to indicate any obstruction or irregularity that may occur and 10 also to indicate when the last ball is taken by the feed-wheel C. This is effected by means of a stud H, which projects into a hole e that has been left unoccupied in such cases, and thereby causes an alarm device to sound 15 or ring.

The arrangement of apparatus herein described, which may be variously modified, enables the balls to be examined very accurately in respect of the exactness of their 20 sphericity, and the results thus produced are not dependent upon the judgment of the observer, as is the case in the apparatus at present in use.

As heretofore stated, the inclined bars are 25 but slightly wider than the diameter of the balls to be tested. In the form of apparatus shown the angle of inclination of the bar is about four degrees, the length of the bar is about fifteen times the circumference of the 30 balls to be tested, and the width of the bar is about one and one-half times the diameter of the balls. While the bars should be much longer than the circumference of the balls to be tested and only very slightly wider than 35 the diameter of the balls, yet I do not desire to be limited to the exact proportions herein set forth.

I claim—

1. In an apparatus for examining balls in 40 respect to the exactness of their sphericity, the combination with a perfectly smooth and true inclined plane over which the balls are allowed to roll, the said inclined plane permitting free escape of diverted bodies over 45 its side edges the breadth of the said plane being but slightly greater than the diameter of the balls to be tested, of a guide at the head of the incline to start the balls in a given line on the inclined surface, and a collecting- 50 box at the end of the inclined plane, substantially as specified.

2. In an apparatus for testing the sphericity of balls, the combination with a feed-wheel provided with peripheral holes, of a guide-channel to which the balls are conveyed by 55 said feed-wheel, smooth stepped inclined bars onto which the balls pass, the said bars being connected by arc-shaped guiding parts, the width of the said bars being but slightly 60 greater than the diameter of the balls to be tested, and the edges of said bars being undefended a receptacle located at the end of the bars, and a receptacle for the balls that

fall over the sides of the bars, substantially as set forth. 65

3. An apparatus for testing the sphericity of balls, the apparatus having a narrow plane and inclined surface whereon the balls may roll, and which is adapted to permit the free escape of the balls over its side edges the 70 width of the said inclined surface being slightly in excess of the diameter of the balls to be tested, and a guide at the head of the inclined surface, the guide serving to start the ball in a given line on the inclined surface, substantially as described. 75

4. An apparatus for testing the sphericity of balls, comprising a receptacle for the balls, a feed-wheel mounted to rotate in the said receptacle and provided with peripheral recesses, a guide-channel to which the balls are delivered one by one from said feed-wheel, and a narrow incline plane onto which the balls are directed from the guide-channel, and which is adapted to permit the free escape of the balls over its side edges a collecting-box at the end of the incline plane, and collecting-boxes arranged to receive the balls that fall over the sides of the incline plane, substantially as set forth. 80

5. An apparatus for testing the sphericity of balls, comprising a receptacle for the balls, a feed-wheel mounted to rotate in the lower part of said receptacle and provided with peripheral recesses, a guide-channel to which 90 the balls are delivered one by one from said feed-wheel, and a series of narrow bars having a smooth inclined upper surface, the first of said bars being in line with the guide-channel, the said bars being inclined in opposite 95 directions, and arc-shaped guides arranged to conduct the balls from one inclined bar to another, substantially as described. 100

6. An apparatus for testing the sphericity of balls, comprising a receptacle into which 105 the balls are placed, a guide-channel into which the balls pass from the receptacle, and a series of bars having a smooth inclined upper surface, the first of said bars being in line with the guide-channel, the said bars being inclined in opposite directions, curved guides arranged to conduct the balls from one inclined bar to the other, a collecting-box arranged to receive the balls that roll to the lower end of the inclined bars, and collecting- 110 boxes arranged to receive the balls that fall over the sides of the inclined bars, substantially 115 as set forth.

In testimony whereof I have signed my name to this specification in the presence of 120 two subscribing witnesses.
